(57) CLAIM

The design for a storage container for collectible items, as shown and described.

DESCRIPTION

The claimed storage container for collectible items is used as a storage container for collectible coins.

FIG. 1 is a perspective view of a storage container for collectible items, embodying my new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is an alternate perspective view thereof, shown in an open position;

FIG. 7 is a left side elevation view thereof; and,

FIG. 8 is a right side elevation view thereof.
